United States Patent

Des. 234,740
Patented Apr. 8, 1975

234,740

KNIFE

Harry Friedman, 263 Gregory Road,
Franklin Lakes, N.J. 07417

Original design application Sept. 7, 1972, Ser. No.
286,982, now Patent No. 229,662. Divided and
this application Aug. 20, 1973, Ser. No. 389,488

Term of patent 14 years

Int. Cl. D8—03

U.S. Cl. D7—150

FIG. 1.

FIG. 2.

FIG. 3.

FIG. 4.

FIG. 5.

FIG. 6.

FIG. 11.

FIG. 12.

FIG. 7.

FIG. 8.

FIG. 9.

FIG. 10.

FIG. 1 is a front elevational view of a knife showing my new design;

FIG. 2 is a top view of the knife of FIG. 1;

FIG. 3 is a rear elevational view of the knife of FIG. 2;

FIG. 4 is a bottom view of the knife of FIG. 2;

FIG. 5 is a right end view of the knife of FIG. 2;

FIG. 6 is a left end view of the knife of FIG. 2;

FIG. 7 is a front elevational view of a modified form of the knife of FIG. 1 wherein the top handle edge is smooth;

FIG. 8 is a top view of the knife of FIG. 7;

FIG. 9 is a rear elevational view of the knife of FIG. 7;

FIG. 10 is a bottom view of the knife of FIG. 7;

FIG. 11 is a right end view of the knife of FIG. 7; and

FIG. 12 is a left end view of the knife of FIG. 7.

This application is a divisional of my application Ser. No. 286,982 for a knife, filed Sept. 7, 1972, now Pat. No. D. 229,662, Dec. 25, 1973.

I claim:

The ornamental design for a knife, as shown and described.
